UNITED STATES PATENT OFFICE.

PATRICK MCENTEE, OF MONTGOMERY, MINNESOTA.

CAR-COUPING.

SPECIFICATION forming part of Letters Patent No. 451,505, dated May 5, 1891.

Application filed May 17, 1890. Serial No. 352,223. (No model.)

To all whom it may concern:

Be it known that I, PATRICK MCENTEE, a citizen of the United States, residing at Montgomery, in the county of Le Sueur and State 5 of Minnesota, have invented certain new and useful Improvements in Car-Couplings, of which the following is a specification.

My invention relates to car-couplings in which the ordinary link and pin are used.

10 The principal object of the invention is to provide devices to prevent accidental uncoupling of the cars while in use. This object is accomplished by the devices illustrated in accompanying drawings, in which—

15 Figure 1 is a front view of the draw-head and a portion of a car provided with my improvements, and Fig. 2 is a central vertical sectional view of the same.

In said drawings, 1 designates the end portion of the frame of the car.

20 2 represents the draw-bar, and 3 a draw-head thereon.

25 In the coupling devices illustrated the pin 4 is lifted out of the pin-hole 5 in the draw-head by means of an angle-plate 6, engaging the head of a pin, and which is connected by a short rod 7 (or a chain) to an arm 8, formed on a rocking rod 9, which is supported in staples 10 on the front end of the car. The 30 rocking rod has a crank 11 at each side of the car for turning it, and a vertical rod 12, connected to a lateral arm 13, for operating it from the top of the car. These devices are similar in character, in a general way, to those 35 disclosed in my application, Serial No. 332,213, filed March 5, 1890.

Other suitable means may, if desired, be employed for lifting the pin.

40 The pin-hole 5, instead of being vertical, is made at a suitable inclination, preferably about eighty-five degrees to the horizontal plane, and in its forward part is a recess 14, terminating in a shoulder 15 above the opening 16 for the link. When a coupling is to 45 be made, the pin is raised by means of the cranks and the rocking rod, (or other means,) so that its point will rest on the shoulder 15. The pin, being thus seated above the slot 16, is in position to be thrown back into the slot 50 by the jar of the two draw-heads in making the coupling. In the inner end of the link-

slot 16 is formed a small recess 17 to permit the end of the link 18 to enter and be held in horizontal position, as indicated in the drawings, thus facilitating the making of a coupling with another draw-head on the same level or a slightly-higher level.

In using links and pins in the ordinary draw-heads the cars frequently become uncoupled while in motion on uneven road-beds, because the jolting of the draw-heads lifts the pins out of the links. This often occurs where one of the draw-heads is higher than the other, so that the connecting-link is in an inclined position and tends to lift 65 the pin in the lower draw-head. By having the pin-hole inclined, as shown, there is no tendency of the link to lift the pin.

As the draw-bars have some play in their slots, there is a tendency on concussion of the 70 heads to rise and fall suddenly, and so displace the pins. I avoid this rising of the draw-head by providing an inclined surface 19 on the top of the draw-bar and causing this incline to engage a surface 20, which may be a 75 plate attached to the under side of the car-frame immediately above the draw-bar, and so when the draw-bar is thrust inward the inclined surface slides on the plate, and the bar, instead of rising, is forced downward while it 80 is being driven inward. The bar, being provided with the usual spring, is returned to its initial outer position when disengaged. Thus by means of the inclined pin-hole and the inclined surface on the outer bar I obviate the 85 danger of displacement of the pin from its link while in use.

What I claim is—

1. In a car-coupling, a draw-bar having an incline on its upper surface, in combination 90 with a fixed object adapted to engage the incline and depress the bar when the latter is thrust inward, substantially as and for the purpose set forth.

2. In a car-coupling, a draw-bar having an 95 incline on its upper surface, a fixed object engaged by the incline to depress the bar, and a draw-head having a pin-hole inclined forward from top to bottom, substantially as set forth.

3. In a car-coupling, a draw-head having a pin-hole inclined forward from top to bottom

and providing a recess, and a shoulder in the front wall to receive and temporarily support a pin, substantially as set forth.

4. In a car-coupling, in combination, a draw-head having a pin-hole inclined forward from top to bottom, a pin, a holder for its head, a rocking rod having a lateral arm, a connec-

tion between said arm and the pin-holder, and cranks for turning the rocking rod, substantially as set forth.

PATRICK MCENTEE.
